UNITED STATES PATENT OFFICE.

LEON K. BELCHER, OF NEW YORK, N. Y.

OIL-BURNER.

1,272,896.

Specification of Letters Patent. Patented July 16, 1918.

Application filed August 15, 1917 - Serial No. 186,358.

To all whom it may concern:

Be it known that I, LEON K. BELCHER, a citizen of the United States, residing at New York, in the county and State of New York, 5 have invented certain new and useful Improvements in Oil-Burners, of which the following is a full, clear, and exact specification.

This invention relates to oil vapor burners, and has for its object to provide a burner of this kind in which the regularity of the flow is assured and there is no danger of flooding. Other objects will appear as the description proceeds.

15 The invention will be first hereinafter described in connection with the accompanying drawings, which constitute part of this specification, and then more specifically defined in the claims at the end of the description.

20 In the accompanying drawings, wherein similar reference characters are used to designate corresponding parts throughout the several views:—

25 Figure 1 is a broken side elevation of a burner constructed substantially in accordance with this invention.

Fig. 2 is a section on the line II—II of Fig. 1, and

30 Fig. 3 is a right hand end view of the burner.

The threaded nipple 1 is designed to be attached to any source of oil supply, and is connected by means of the threads at one 35 end to the T-coupling 3. The middle portion of the nipple between its threaded ends is formed with a wrench surface 2 for turning it up. The T-coupling 3 is connected to a gas generating pipe or chamber 4 extending 40 horizontally and filled with a plurality of rods 5, for retarding the flow of the oil through said pipe. The other end of the pipe 4 is connected to an elbow 6 which is turned upward and connected to another 45 elbow 7 leading to another horizontal pipe 8 arranged above and a little to one side of the pipe 4. The other end of the pipe 8 is attached to a reducing elbow 9 which is turned downward and connected to a smaller 50 gage pipe 10 which is attached by means of an elbow 11 on its lower end to the horizontal burner pipe 12 the free end of which is stopped by a plug or cap 14.

The T-coupling 3 is also attached to a depending solid rod 15 which is fastened at 55 its lower end to a block 16, whereby one end

of the burner is supported. The other end of the burner is supported by another block 17 similar to the block 16 except that instead of the rod 15, it is provided with an upward projection 19 on which the free end 60 of the burner pipe 12 rests. The two blocks 16 and 17 are connected by a trough 18 extending directly below the burner pipe, which in turn is directly below the gas generating pipe 4, the pipe 8, which will be called the drying and expansion pipe or chamber, being above and in the vertical plane determined by the generating pipe 4 and the burner pipe 12. The flames from 70 the openings 13 in said burner pipe play directly upon the generating pipe 4, and owing to the presence of the filling of rods therein which break up as well as retard the flow of the oil, the latter is quickly converted 75 into vapor capable of burning with a blue flame.

The vaporization of the oil and the proper feeding thereof to the burner pipe is greatly improved by the use of the pipe 8 which 80 dries the gas generated in the pipe 4 to some extent and allows said gas to expand, and by the reducing elbow 9 and pipe 10, which further retard the flow of the vapor to the burner pipe. The generating pipe 4 carries 85 a pair of flame deflectors 20 arranged above the openings 13 in the burner pipe 12. These deflectors may be adjusted by means of the set screws 21 to different inclination toward either side, as suggested in dotted 90 lines in Fig. 2, for directing the flames against a waterback or an oven, by one flame in one direction and the other flame in the opposite direction, as desired.

When the oil supply is first turned on to 95 the pipe 4 through the nipple 1, a small quantity of inflammable material 22, Fig. 2, is placed in the trough 18 and ignited, so that the flame therefrom will act in place of the flames from the burner pipe 12 for 100 vaporizing the oil as it passes through the pipe 4. By the time the vapor has been formed and reaches the burner pipe, it will be in condition to burn and will be ignited by the flame from the material in the trough, 105 so that when said material burns out, the burner will continue to operate without interruption.

The pipe 8, as well as the pipe 4, is filled with rods 5 to retard a flow of the oil 110 through the same. The pipe 10 is curved, as shown in Figs. 2 and 3, to bring the

burner pipe 12 directly below the pipe 4, and the pipe 8 at least three-fourths of its diameter over the pipe 4, so that said pipe 8 is protected from the direct heat of the flames from the burner pipe 12 by the pipe 4 and the deflectors 20 mounted thereon.

Having thus described my invention, what I claim as new and desire to secure by Letters Patent of the United States is:

- 10 1. In a burner of the character described, the combination with a burner, of a generating pipe arranged directly over the burner, flame deflectors on said generating pipe, a drying and expansion pipe arranged over 15 the generating pipe and communicating therewith, said drying and expansion pipe being protected from the flame by the generating pipe and the deflectors thereon, and

a pipe of smaller gage than the drying and expansion pipe leading therefrom to the 20 burner.

2. In a burner of the character described, the combination with a burner, of a generating pipe arranged directly over the burner, a drying and expansion pipe arranged above 25 the generating pipe, means of communication between one end of the drying and expansion pipe and the generating pipe and between the other end of said drying and expansion pipe and the burner, and fillings of 30 rods in the generating pipe and drying and expansion pipe for retarding the flow in said pipes.

In testimony whereof I have signed my name to this specification.

LEON K. BELCHER.
